UNITED STATES PATENT OFFICE

149,829

DESIGN FOR A STEERING WHEEL KNOB

Edward S. Mungen, Manhattan Beach, Calif., assignor to Cal-Pan Associates, Inglewood, Calif., a copartnership consisting of Herbert L. Trautmann and Edmund C. Trautmann

Application October 9, 1946, Serial No. 133,837

Term of patent 14 years

(Cl. D14—6)

To all whom it may concern:

Be it known that I, Edward S. Mungen, a citizen of the United States, residing at Manhattan Beach, in the county of Los Angeles and State of California, have invented a new, original, and ornamental Design for a Steering Wheel Knob, of which the following is a specification, reference being had to the accompanying drawing, forming a part thereof.

Fig. 1 of the drawing is a perspective view of the steering wheel knob embodying my new design;

Fig. 2 is a perspective view of the same showing the under side thereof;

Fig. 3 is a side elevational view of the same; and
Fig. 4 is a front elevational view of the same.

The dotted line showing in Figs. 1 and 3 is for illustrative purposes only.

I claim:

The ornamental design for a steering wheel knob, as shown and described.

EDWARD S. MUNGEN.
